[57] ABSTRACT

A drawer suspension system including a pair of roller mounting hinged leaves and a pair of drawer mounted rollers, which cooperate with a cabinet mounted trackway and guide tracks to provide cantilever support for the drawer in open position.

CABINET DRAWER SUSPENSION SYSTEM

SUMMARY OF THE INVENTION

The present invention broadly relates to improvements in drawer suspension devices of the type affording cantilever support for the drawer when in open position.

The drawer suspension device of the present invention generally includes a pair of roller mounting leaves, which are hingedly connected to the drawer adjacent rear corner edges thereof; a pair of rollers, which are carried by the sides of the drawer adjacent its rear corner edges for rolling engagement with drawer supporting guide rails; and a curved trackway for cooperating with certain of the leaf mounted rollers to control opening and closing movements of the leaves. Others of the leaf mounted rollers cooperate with the drawer carried rollers to provide a cantilever support for the drawer when in open position.

More specifically, each leaf is provided with a first roller, which is rotatable about a vertical axis and arranged to engage with the curved trackway, and a second roller, which is rotatable about a horizontal axis and cooperates with an associated drawer mounted roller and guide rail to provide a cantilever support for the drawer. A pair of cabinet mounted rollers serves to support the front of the drawer while in closed position and may serve as abutments for the drawer mounted rollers in order to define the full open position of the drawer.

In a preferred form of the present invention, spring devices are employed to bias the leaves "in", that is, towards their folded or drawer closed position. This construction serves to render the drawer self closing after the drawer has been closed beyond that point necessary to place the first rollers in engagement with the curved trackway, and to prevent or reduce "racking" or "yawing" of the drawer as it moves in and out of the cabinet.

The present invention additionally features a novel drawer construction, wherein hinge part halves are integrally formed on opposite ends of the drawer rear wall and the leaves, whereby to permit the leaves to be hingedly secured to the drawer by the simple operation of inserting a pair of hinge pins through associated ones of the hinge part halves.

While the present invention is primarily intended for use as a suspension for filing cabinet drawers, it will be readily appreciated that the present construction has utility whenever it is desired to support a drawer or other supporting platform during movement relative to a supporting frame from a closed or retracted position, wherein front and rear ends of the drawer are readily supported, to an open or extended position, wherein the weight of the drawer or articles supported thereby tends to tilt the front or extended end of the drawer downwardly relative to the frame. Thus, the terms "cabinet" and "drawer", when employed in the following detailed description and appended claims, are meant to include the terms "frame" and "platform", respectively, as well as equivalent structures.

DRAWINGS

The nature and mode of the present invention will now be more fully described in the following detailed description taken with the accompanying drawings wherein:

FIG. 1 is an exploded perspective view of the suspension device of the present invention in combination with a cabinet and drawer, with parts broken away for purposes of clarity;

FIG. 2 is a sectional view taken through the rear wall of the drawer and showing one leaf device extended rearwardly of the drawer;

FIG. 3 is a top plan view of the structure shown in FIG. 1 and illustrating the relative placement of parts during successive stages of drawer opening movements;

FIG. 4 is a sectional view taken generally along line 4-4 in FIG. 2;

FIG. 5 is a sectional view taken generally along line 5-5 in FIG. 3;

FIG. 6 is a sectional view taken generally along line 6-6 in FIG. 3;

FIG. 7 is an enlarged view of the area designated as FIG. 7 in FIG. 3;

FIG. 8 is a fragmentary, exploded perspective view illustrating a preferred mode of attaching a leaf device to a drawer;

FIG. 9 is a fragmentary perspective view illustrating an alternative form of the present invention; and

FIG. 10 is a fragmentary perspective view illustrating another alternative form of the present invention.

DETAILED DESCRIPTION

Reference is now made particularly to FIG. 1, wherein a suspension system according to a preferred form of the present invention is shown as being employed to support a drawer 12 within a cabinet 14 for reciprocating movements between drawer closed and opened positions. For purposes of reference, drawer 12 is shown as being of sheet metal construction and as generally including front, rear, side and bottom walls 16 through 19, respectively. Side walls 18 may be contoured to define lengthwise extending support ledges or ribs 20, and cabinet 14 may include in part side and rear walls 22 and 24, respectively. While drawer 12 and cabinet 14 may be of any conventional construction, a preferred drawer rear wall design will hereinafter be described.

More specifically, the preferred form of the suspension system includes a pair of horizontally disposed guide tracks 26, which are suitably fixed to cabinet walls 22 and formed with lower and upper flanges 26a and 26b, respectively; a first pair of drawer supporting rollers 28, which are carried in axial alignment adjacent the rear ends of drawer side walls 18; a second pair of axially aligned drawer supporting rollers 30, which are fixed to cabinet walls 22 adjacent the forward ends of guide tracks 26; a pair of leaf devices 32, which are mounted adjacent the rear corner edges of drawer 12 by a pair of hinge devices 34 for pivotal movements about parallel vertically disposed axes; and a cabinet mounted guide trackway generally designated as 36. As will be apparent, rollers 28 bear downwardly against the lower or bottom flange 26a of guide tracks 26 (FIG. 2) and the downwardly facing surfaces of ledges 20 rest on rollers 30 (FIGS. 2 and 5) in order to support

drawer 12 relative to cabinet 14, while the drawer is closed and at least during an initial portion of its travel towards fully open position.

Trackway 36 is best shown in FIGS. 1 and 3 as including a rear or main portion 38, which defines a generally planar surface 40 arranged to lie flush with or slightly below the upwardly facing surfaces of guide track lower or bottom flanges 26a and an upwardly opening arcuate guide track 42, which is essentially semi-circular when viewed in plan. Trackway 36 additionally includes forward portions in the form of extension trackways 44, which connect with opposite ends of guide track 42 and extend forwardly therefrom in parallel relationship with channels 26. Guide track 42 is bounded by inner and outer arcuate guide flanges 42a and 42b, respectively and a connecting bottom flange 42c, whereas extension trackways 44 are each bounded by inner and outer guide flanges 44a and 44b, respectively, and a connecting bottom flange 44c. Construction may be facilitated, if desired, by forming extension trackways 44 integrally with guide tracks 26, as indicated in FIG. 4.

Reference is now made particularly to FIGS. 1-4, wherein each of leaf devices 32 is shown as including a tapered channel member formed from sheet metal to define a main upstanding flange portion 46a and upper and lower reinforcing flanges 46b and 46c, respectively; and first and second follower members, which are in the form of follower rollers 48 and 50 journaled adjacent the free swinging ends of flanges 46c and 46a for rotation about essentially vertically and horizontally disposed axes, respectively.

In a preferred drawer construction, best shown in FIGS. 2, 7 and 8, rear wall 17 is of a box or pan shaped configuration including a recessed central portion 17a bounded by rearwardly extending top, bottom and end reinforcing flanges 17b-17d; flanges 17c and 17d being suitably fixed to bottom and side walls 19 and 18 respectively. By recessing central portion 17a, by arranging leaf device lower flanges 46c below the level of drawer bottom wall 19 and by forming leaf devices 32 of a length less than about one half the width of the drawer rear wall, the leaf devices may be folded into a first or drawer fully closed position thereof, wherein they nest within and extend transversely of the rear of drawer 12 as best shown in FIG. 1. Also in accordance with the preferred drawer construction, one hinge part of each of hinge devices 34 is defined by bending end flanges 17d to form a plurality of hinge knuckles 34a, as best shown in FIGS. 2, 7 and 8. Another hinge part of each of hinge devices 34 is defined by bending the enlarged end of each of leaf device main flanges 46a to form a plurality of hinge knuckles 34b. The forming of the respective hinge parts integrally with the leaf devices and the drawer rear wall, greatly facilitates fabrication procedures, since the leaf devices may be assembled on the drawer by merely passing hinge pins 34c downwardly through hinge knuckles 34a and 34b. Hinge devices 34 also preferably include coil spring devices 34d, which engage with stops 34e and 34f formed on leaf device upper flange 46d and rear wall top flange 17b, respectively, for the purpose of normally biasing the leaf devices towards one another into engagement with the relatively inner guide flanges 42a and 44a of guide track 42 and guide track extension 44.

To facilitate understanding of the mode of operation of the present invention, specific reference is now

made to FIG. 3, wherein the drawer is shown in a plurality of positions including a first or fully closed phantom line position designated at 12a; a second or partially open full line position designated at 12b; and a third or fully open phantom line position designated at 12c.

As indicated above, when the drawer is in its fully closed position, it is supported by engagement of rollers 28 with the lower guide flanges 26a adjacent the rear end of guide tracks 26 near rear wall 22 and by engagement of cabinet mounted rollers 30 with the forwardly extending ends of drawer side wall ledges 20. In this position of the drawer, leaf devices 32 are folded into their closed or first position wherein they extend transversely of the rear of the drawer; their associated followers 48 being biased by spring devices 34d into engagement with inner flanges 42a of guide track 42 adjacent a mid-point thereof, while their follower rollers 50 merely rest on or spaced slightly above upper trackway surface 40.

As the drawer is opened, follower rollers 48 are forced to move apart towards the ends of guide track 42 by engagement with inner flanges 42a whereby to progressively swing leaf devices apart into an open or second position in which they extend rearwardly of the drawer in a parallel relationship and their associated follower rollers 50 are arranged vertically intermediate guide flanges 26a and 26b and their associated follower rollers 48 are disposed adjacent the junction of the inner flanges 42a and 44a, as shown in full line in FIG. 3. At this point of drawer opening movement, the drawer is still normally supported by rollers 28 and 30, but in that rollers 30 now engage with the drawer side wall ledges 20 adjacent to or rearwardly of mid-points thereof, there may be a tendency for the drawer to tilt forward about rollers 30 if heavy drawer contents are arranged adjacent the front of the drawer. In accordance with the present invention, tilting movement of the drawer, during opening movements thereof from its intermediate position towards and into its fully opened position, is effectively prevented by engagement of follower rollers 50 with the lower surface of upper guide flanges 26a adjacent mid-points of guide tracks 26. The fully open position of the drawer may be conveniently defined by engagement of rollers 28 with rollers 30; it being noted from FIG. 2 that even in this position rollers 50 are spaced rearwardly of rollers 30 to provide an effective cantilever support for the drawer and its contents. While unnecessary for most drawer installations, it would of course be possible to also provide a curved trackway above surface 40 for engagement by rollers 50 in order to prevent drawer tilting movements even before the drawer has been moved outwardly into its intermediate position.

As by way of comparison, in a conventional drawer construction excessive tilting of the drawer in its intermediate position would be arrested by movement of drawer mounted rollers 28 into engagement with the lower surfaces of upper flanges 26b adjacent to or forwardly of mid-points of guide tracks 26. However, during further opening movement of the drawer, the distance between rollers 28 and 30 decreases until some point is reached before the door is fully opened at which the rollers are unable to effectively support the drawer. Thus, it will be seen that the present suspension system permits a drawer to be opened through a greater distance than that allowed by a conventional system by

an amount which essentially corresponds to the length of the leaf devices, that is, about one-half of the width of the drawer. Also, it will be understood that the utilization of spring devices 34d to bias rollers 48 into engagement with guide surfaces 42a and 44a tends to prevent or reduce "racking" or "yawing" of the drawer, during all opening and closing movements thereof, and that after the drawer has been moved inwardly past its intermediate position spring device 34d tends to bias the drawer into fully closed position.

FIG. 9 illustrates a modified, heavy duty leaf device design 32', which incorporates an extra follower roller 50' arranged to bear upwardly against the lower surface of a lower flange 26a' of a guide track 26' associated with a vertically adjacent drawer, not shown, or in the case of a top drawer, against the inner surface of top wall of a cabinet, also not shown. As a result, loads are divided between rollers 50 and 50' and guide tracks 26 and 26'. If desired, rollers 50' could also be arranged to bear upwardly against the trackway associated with a vertically adjacent drawer in order to permit the leaf devices to oppose drawer tilting movements before the drawer has been opened into its intermediate position.

FIG. 10 illustrates another form of the present invention, wherein leaf devices 32'' each have a length in excess of one-half the width of the drawer with a view to providing an even more effective cantilever support for the drawer. Leaf devices 32'' may be swung into essentially parallel overlapping relationship when the drawer is fully closed, by merely arranging their associated hinge devices 34' in a rearwardly staggered relationship. With this construction, it would of course be necessary to modify the previously described trackway in order to accommodate follower rollers 48' during swinging movements of the leaf devices.

I claim:

1. In a cabinet construction, the combination comprising:

a cabinet frame defining an opening;
a drawer;

a pair of spaced horizontally elongated guide tracks carried by said frame to extend rearwardly within said frame from adjacent opposite sides of said opening, said guide tracks having vertically spaced upper and lower guide flanges;

a first pair of drawer supporting rollers fixed to opposite sides of said drawer in axial alignment and adjacent a rear end thereof, said rollers of said first pair being arranged to bear downwardly one against each of said lower flanges;

a pair of leaf devices hingedly secured to said drawer one adjacent each rear end corner thereof for pivotal movements in opposite directions about parallel vertically disposed axes between first and second positions, each said leaf device carrying first and second follower rollers, each of said first follower rollers being mounted for rotation about a vertically disposed axis, each of said second follower rollers being mounted for rotation about a horizontally disposed axis and arranged to bear upwardly against one of said upper flanges when said leaf devices are in said second position for thereafter constraining forward and downward tilting of said drawer;

horizontally disposed trackway means fixed to said frame and cooperating with said first follower rol-

lers for pivoting said leaf devices between said first position in which said leaf devices are disposed to extend transversely of said drawer when in closed position and said second position in which said leaf devices are disposed to extend rearwardly of said drawer when in at least partially open position, said first follower rollers being disposed adjacent a midpoint of said trackway means when said drawer is in said closed position and being moved apart towards opposite ends of said trackway means upon opening of said drawer into said partially open position, said trackway means additionally defining a pair of extension trackways extending forwardly one from each of said opposite ends parallel to said guide tracks for guidingly receiving said first follower rollers whereby to constrain said leaf devices in said second position thereof during continued opening movement of said drawer beyond said partially open position; and

further means for supporting portions of said drawer forwardly of said rear end thereof relative to said frame at least during opening movements of said drawer occasioning movement of said leaf devices from said first to said second position thereof, said further means including a second pair of drawer supporting rollers carried by said frame in axial alignment adjacent forwardly extending ends of said guide tracks for engagement with said drawer, and the rollers of said first and second pairs being aligned in the direction of drawer movements, whereby the extent of said continued opening movement of said drawer beyond said partially open position is determined by engagement of the rollers of said first pair with the rollers of said second pair.

2. A device according to claim 1, wherein each said leaf device includes spring means tending to bias its associated leaf device from said second into said first position thereof.

3. A cabinet construction according to claim 1, wherein said drawer includes side, bottom, front and rear walls, at least said rear walls being formed separately of the other of said walls and being fixed adjacent horizontally opposite ends thereof at least to said side walls adjacent rear ends thereof, said leaf devices being hingedly secured to said drawer by a pair of hinge means each including a first hinge part formed integrally with one of said opposite ends of said rear wall, second hinge part formed integrally with one of said leaf devices and hinge pin for joining said first and second hinge parts, and each of said hinge means carries a coil spring tending to bias its associated leaf device from said second into said first position thereof.

4. In a cabinet construction, in combination comprising:

a cabinet frame defining an opening;
a drawer, said drawer having downwardly facing support ledges extending outwardly and lengthwise of its opposite side walls;

a pair of spaced horizontally elongated guide tracks carried by said frame to extend rearwardly within said frame from adjacent opposite sides of said opening, said guide tracks being of U-shaped configuration and having vertically spaced upper and lower guide flanges;

a first pair of drawer supporting rollers fixed to opposite sides of said drawer in axial alignment and ad-

jacent a rear end thereof, said rollers of said first pair being arranged to bear downwardly one against each of said lower flanges; a pair of leaf devices hingedly secured to said drawer one adjacent each rear end corner thereof for pivotal movements in opposite directions about parallel vertically disposed axes between first and second positions, each said leaf devices carrying first and second followers, said second followers being second follower rollers mounted for rotation about a horizontally disposed axis and arranged to bear upwardly against one of said upper flanges when said leaf devices are in said second position for thereafter constraining forward and downward tilting of said drawer; horizontally disposed trackway means fixed to said frame and cooperating with said first followers for pivoting said leaf devices between said first position in which said leaf devices are disposed to extend transversely of said drawer when in closed position and said second position in which said leaf devices are disposed to extend rearwardly of said drawer when in at least partially open position, said first followers being disposed adjacent a mid-point of said trackway means when said drawer is in said closed position and being moved apart towards opposite ends of said trackway means upon opening of said drawer into said partially open position, said trackway means additionally defining a pair of ex-

tension trackways extending forwardly one from each of said opposite ends parallel to said guide tracks for guidingly receiving said first followers whereby to constrain said leaf devices in said second position thereof during continued opening movement of said drawer beyond said partially open position;

a second pair of drawer supporting rollers carried by said frame in axial alignment and adjacent forwardly extending ends of said guide tracks for under-engaging said support ledges, said support ledges being disposed vertically above said upper guide flanges, said rollers of said first and second pairs being aligned in the direction of drawer movements, whereby the extent of said continued opening movement of said drawer beyond said partially open position is determined by engagement of the rollers of said first pair with the rollers of said second pair; and

spring means tending to continuously bias said leaf devices from said second position into said first position thereof, whereby said first followers are caused to bear against said trackway means including said extension trackways to constrain yawing of said drawer during opening and closing movements thereof and to bias said drawer towards closed position for positions thereof intermediate said closed position and said partially open position.
